PORTABLE RADIO OR SIMILAR ARTICLE

Victor Reichenstein, Great Neck, N.Y., assignor, by mesne assignments, to U.S. Industries, Inc., New York, N.Y., a corporation of Delaware

Filed June 11, 1968, Ser. No. 12,295

Term of patent 7 years

Int. Cl. D14—03

U.S. Cl. D56—4

FIG. 1 is a front elevational view of a portable radio or similar article showing my new design;
FIG. 2 is a bottom plan view thereof;
FIG. 3 is a top plan view thereof;
FIG. 4 is a right side elevational view thereof;
FIG. 5 is a left side elevational view thereof, and
FIG. 6 is a rear elevational view thereof on a reduced scale.

I claim:

The ornamental design for a portable radio or similar article, substantially as shown.
